UNITED STATES PATENT OFFICE.

VALENTINE E. WIGGINTON, OF WASHINGTON COURT-HOUSE, OHIO.

KITCHEN-CABINET.

SPECIFICATION forming part of Letters Patent No. 365,289, dated June 21, 1887.

Application filed April 28, 1887. Serial No. 2 6,449. (No model.)

To all whom it may concern:

Be it known that I, VALENTINE E. WIGGINTON, a citizen of the United States of America, residing at Washington Court-House, in the 5 county of Fayette and State of Ohio, have invented certain new and useful Improvements in Kitchen-Cabinets; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification.

15 My invention relates to certain new and useful improvements in kitchen-safes, the object of my invention being designed more especially to provide a means for securing the kneading-board thereto, so that it can be placed, 20 when not in use, in a nearly-vertical position, and will form a front for the cabinet to which it is applied; and with the above ends in view my invention consists in the construction and combination of the parts, as will be hereinafter fully set forth, and specifically pointed out 25 in the claims.

In the accompanying drawings, which illustrate my invention, Figure 1 is a perspective view of a kitchen-cabinet showing my improved 30 kneading-board applied thereto, said kneading-board being closed so as to occupy a vertical position. Fig. 2 is a vertical sectional view showing the kneading-board in a horizontal position. Fig. 3 is a transverse sectional view taken through the line xx of Fig. 35 2. Fig. 4 is a plan view of the upper edge of the kneading-board. Fig. 5 is a detail perspective view of one of the corner-irons which are attached to the rear inner corners of the 40 45 kneading-board; and Fig. 6 is a detail view of a connection which is pivotally secured to the frame of the cabinet and to the corner-iron attached to the kneading-board.

In the accompanying drawings, A refers to 45 a kitchen-cabinet, which may be of ordinary construction, the same being provided with an upper portion having shoulders and doors, while the lower portion, which projects at its front beyond the upper portion, is provided 50 with meal and flour bins having sliding boards, which cover the same and form tops for said

bins as well as a shelf. The vertical sides of the lower portion of the cabinet are provided with a series of small drawers, between which drawers the kneading-board B is secured. The meal 55 and flour bins hereinbefore referred to do not extend to the front of the lower portion of the cabinet, and a central space is provided between the drawers C and in front of the bins C'.

D refers to vertical boards or side pieces, 60 which are provided on each side with metallic guide-strips d, which are provided centrally with slots d', these guide-pieces being curved horizontally at their upper ends, as shown at e in Fig. 2.

B refers to the kneading-board, which is made up of a bottom board, b, side pieces b', which taper or incline from the back edge to the front, so as to form side pieces, and to the transverse back piece, b'', and side pieces b' are attached, 70 by suitable screws, corner-irons E, which corner-irons are provided at their upper ends with a perforated portion, F, which will extend over the edge of the transverse board b''.

G refers to a metallic connection, which has 75 the ends bent so as to project at right angles in opposite directions from the body portion, which is of about the same length as the width of the transverse board b'', and these projecting portions are provided with eyes g g', the eyes 80 g being secured to the projecting portion F by a rod, H, which extends across the upper edge of the board b'' and passes through the eyes g and through the perforations in the portion F, the end of this rod engaging with the slots d' 85 in the guide-strips d. The lower eyes, g', of the portion G are also connected to the slotted guide-strips by a rod, I, which passes through said eyes and enters the slots d'.

The slotted guide-strips hereinbefore referred to are attached to the side pieces D, at an angle with the front edge, as shown in Fig. 2, said angle corresponding approximately with the width of the side pieces b' of the kneading-board, so that when it is folded in a vertical position, as shown in Fig. 1, it will be flush 95 or parallel with the front edges of the boards D.

When it is desired to place the kneading-board in a position for use, the upper edge of the same is drawn slightly downwardly, and 100 said board is elevated and then swung to a horizontal position. This will cause the up-

per rod to move into the horizontal portion of the slot, and the pressure or weight of the kneading-board will cause the rod H to press toward the front edge of the horizontal slot, 5 while the lower rod, I, is pressed rearwardly, thus holding the kneading-board securely in a horizontal position.

When it is desired to lower the board, the front end is slightly elevated and pressed rearwardly, so as to cause the rod H to enter the vertical portion of the slot, when the rear end may slide downwardly and swing in a vertical position, and be secured in such a position by a button or catch. The corner-iron E not only 15 provides a means for attaching the connection G thereto, but also serves to brace the rear portion of the kneading-board.

Instead of employing rods which extend entirely across the front, as hereinbefore described, I may employ short bolts or pins.

I claim—

1. In a kitchen-cabinet provided with a recessed portion at its front, slotted guide-strips having their upper ends bent horizontally, 25 corner-irons E, attached to a kneading-board, and connecting portions G, pivotally secured to said corner-irons and connected by rods to the slotted guide-strips, substantially as shown, and for the purpose set forth.

2. In combination with a kneading-board, 30 slotted guide-strips d, corner-irons E, with rearwardly-projecting perforated portions F, links G, with perforated ends, and rods H and I, the parts being organized substantially as shown, and for the purpose set forth.

3. In combination with a kneading-board of a kitchen-cabinet, said kneading-board consisting of a bottom board, side pieces, and a back piece, corner-irons attached to said kneading-board and provided with rearwardly-extending perforated portions, connecting-links having a straight central portion, and end portions with eyes bent in opposite directions, rods H, for attaching the parts to each other, and a rod, I, said rods engaging with inclined 45 slotted guide-plates having horizontal upper portions, said guide-plates being attached to the supporting-frame, whereby the kneading-board can be elevated and held in a horizontal position or be brought to a vertical position, 50 substantially as shown, and for the purpose set forth.

In testimony whereof I affix my signature in presence of two witnesses.

VALENTINE E. WIGGINTON.
